(57) **CLAIM**

The ornamental design of a bottle, as shown and described.

DESCRIPTION

FIG. 1 is front elevation view of the bottle according to a first embodiment of the present invention.

FIG. 2 is rear elevation view of the bottle according to a first embodiment of the present invention.

FIG. 3 is right side elevation view of the bottle according to a first embodiment of the present invention.

FIG. 4 is top plan view of the bottle according to a first embodiment of the present invention.

FIG. 5 is the perspective view of the bottle according to a first embodiment of the present invention.

FIG. 6 is top plan view of the bottle according to a first embodiment of the present invention with the cap removed.

FIG. 7 is front elevation view of the bottle according to a second embodiment of the present invention.

FIG. 8 is rear elevation view of the bottle according to a second embodiment of the present invention.

FIG. 9 is right side elevation view of the bottle according to a second embodiment of the present invention.

FIG. 10 is top plan view of the bottle according to a second embodiment of the present invention.

FIG. 11 is the perspective view of the bottle according to a second embodiment of the present invention.

FIG. 12 is the 2nd perspective view of the bottle according to a second embodiment of the present invention.

FIG. 13 is top plan view of the bottle according to a second embodiment of the present invention with the cap removed.

FIG. 14 is front elevation view of the bottle according to a third embodiment of the present invention.

FIG. 15 is rear elevation view of the bottle according to a third embodiment of the present invention.

FIG. 16 is right side elevation view of the bottle according to a third embodiment of the present invention.

FIG. 17 is top plan view of the bottle according to a third embodiment of the present invention with the cap removed.

FIG. 18 is the perspective view of the bottle according to a third embodiment of the present invention.

FIG. 19 is the perspective view of the transparent cap of the bottle according to a third embodiment of the present invention.

FIG. 20 is front elevation view of the bottle according to a forth embodiment of the present invention.

FIG. 21 is rear elevation view of the bottle according to a forth embodiment of the present invention.

FIG. 22 is right side elevation view of the bottle according to a forth embodiment of the present invention.

FIG. 23 is top plan view of the bottle according to a forth embodiment of the present invention; and, FIG. 24 is the perspective view of the bottle according to a forth embodiment of the present invention.

The broken lines shown are included for the purpose of illustrating the unclaimed portions of the bottle and form no part of the claim.
